JOHN S. BOOTH, OF DALLAS, TEXAS, ASSIGNOR TO ZERO PLATE CORPORATION, A CORPORATION OF DELAWARE

REFRIGERATOR AND COOLING UNIT THEREFOR

Application filed November 16, 1931. Serial No. 575,447.

My invention relates to refrigerators and cooling units therefor and more particularly to such devices of the so-called mechanical type wherein the desired low temperatures for preservation of foodstuffs or other perishable commodities are obtained through mediums other than ice.

Heretofore, the mechanical refrigerators and cooling units which have been used, of course, obviated the necessity of periodical attention and icing, but they were not otherwise as satisfactory as the old type ice box. In the first place, most mechanical refrigerators were sealed chambers with no outward flow of gases or other liquids given off by perishable articles contained therein; and, in the second place, articles in the refrigerator were dehydrated when moisture in the air was condensed as frost on the cooling coils of the mechanical unit.

It is a well known fact that refrigerators utilizing ice or a mixture of ice and salt as a refrigerant did not have these deficiencies of structure. Obviously, as ice refrigerators depend upon the melting of the ice for cooling, it was necessary to have a drain from the refrigerant compartment or container through which passed the water incidental to such melting. This drain after a period of time would become filled with a thick mass or jelly which was usually thought to be vapors or gases given off by the foodstuffs in the storage compartment of the refrigerator and condensed by contact with ice. Much of this condensation was carried off through the drain with the flow of water. Also, the use of ice impregnated the air in the refrigerator with sufficient moisture to prevent dehydration of articles stored therein.

Furthermore, mechanical units used in the past depended upon convection currents to cool the interior of the refrigerator and in devices providing for an intermittent supply of cooling agent to the cooling coils these currents were strongest during the period when the cooling agent was being actively supplied and were weakest in the "carry over" period when the cooling agent was inactive. Consequently, during the "carry

over" period the cooling coils had very little refrigerating effect and, therefore, in such mechanical units the mechanism for actively supplying the cooling agent was operating about fifty percent of the time.

The objects of my invention are to provide a device which will have all the advantages of a mechanical unit but also will have the advantages attendant the use of ice as a refrigerant; and to provide a mechanical unit in which the "carry over" period will be greatly lengthened with a resultant saving in the cost of operation.

Although I do not propose to limit the use of my invention to any particular form of refrigerator, in the accompanying drawings, wherein similar characters are used to designate similar parts, I have shown my invention embodied in a show case refrigerator such as commonly used in markets or florist shops and I have also shown my invention embodied in a cooler in which meat or other perishable commodities are stored. It is to be understood, however, that with equal facility my invention may be embodied in household refrigerators or in refrigerators of any other type.

In the drawings, Fig. 1 is a perspective, partly in section, of a show case refrigerator and cooling unit made according to my invention; Fig. 2 is a similar view of a cooler; Fig. 3 is a top plan view of the cooling unit shown in the embodiment of Fig. 1; Fig. 4 is a side view of the unit partly in section; and Fig. 5 is a section along the lines 4-4 in Fig. 4.

Referring to the figures and particularly to the embodiment shown in Figs. 1, 3, 4 and 5 the show case refrigerator comprises in the usual form a cabinet 1 having a front transparent panel 2 and top transparent panels 3 through which are visible foodstuffs or other perishable articles arranged on the shelf 4 and along the bottom wall of the storage compartment, which wall, in this embodiment, is also the top wall of the refrigerating compartment, as will be more fully hereinafter explained. Access to the storage compartment is had through doors 5 fitted in suitable openings in the rear of the show case.

The cooling unit in refrigerators of this type may be arranged along the bottom thereof as shown in Fig. 1, and is preferably substantially coextensive therewith, for reasons to be later explained. As shown herein the cooling unit comprises a casing 6 which has the top and side walls thereof formed by hoodlike sections so that it may be readily assembled or disassembled and has a bottom wall 7 extending along the bottom of the refrigerator and provided with up-turned flanges 7' which engage the lower ends of the side walls of the sections. The casing 6 has at one end thereof a flue 8 provided with an inlet opening and has at the other end thereof a flue 9 provided with an outlet opening. I prefer that the upper portions of the flues 8 and 9 be above the plane of the elongated portion of the casing 6 and the inlet and outlet openings may be screened, as shown in the figures. I prefer that the casing 6 with its included flues 8 and 9 and bottom wall 7 be formed of metal or any other conductive material. I also prefer that the top wall of the longitudinally extending portion of the casing be arranged as shown so that, as stated above, it will form a bottom wall for the storage compartment of the refrigerator and will, therefore, separate the refrigerating compartment from the storage compartment. Mounted in the inlet flue 8 so as to create a draft or suction from the storage compartment through the inlet opening is a fan 10, preferably electrically driven.

Arranged in the refrigerating compartment formed by the casing 6 and preferably coextensive therewith is a cooling coil 11 which is positioned in this embodiment with the convolutions extending substantially transversely of the compartment as shown in Fig. 3. To facilitate removal for cleaning or repair the coil 11 may be formed in sections with adjacent ends of adjacent sections connected by means of a coupling 12. A plurality of longitudinally extending fins 13 to regulate the flow of air through the refrigerating compartment, as described below, are mounted within the convolutions of the coil, as shown particularly in Fig. 5. The longitudinally extending rails 14 are fixed to the upper and lower faces of the coils to form a conductive connection between the coil and the top wall of the casing 6 and the bottom wall 7 and to support said top wall. A drain pipe 15 leads from a suitable sump to an outside place of discharge whereby water collected on the bottom wall 7 may flow from the case.

A cooling agent is supplied by any suitable mechanism, not shown, to the coil 11 through a supply pipe 16 and, after flowing through the coil, the agent enters the return pipe 17. I prefer that the supply pipe 16 be positioned near the inlet end of the refrigerating compartment and that the return pipe

17 be positioned near the opposite or outlet end so that the general direction of the flow of cooling agent through the coil will be the same as that of the circulation of air created by the fan 10 through the refrigerating compartment, all for the reasons explained below.

In the embodiment of my invention shown in Fig. 2 the cooler 18 may be entered through the door 19. In this installation I prefer that the cooling unit be mounted on the upper wall or ceiling so that the casing 6^a thereof depends from the top of the cooler. The inlet flue 8^a and outlet flue 9^a are similar to the flues of the other embodiment and circulation through the refrigerating compartment formed by the casing 6^a is created by a fan 10^a. Because of the great amount of space to be cooled the coils 11^a are arranged in upper and lower tiers with the cooling agent entering through a supply pipe 16^a, and flowing in one direction through the upper tier of the coil, in a reverse direction through the lower tier and out through the return pipe 17^a. Fins 13^a are provided in each tier of the coil and rails 14^a are provided to maintain the tiers in fixed position. A drain pipe 15^a is arranged to carry water from the unit, all as shown in the figure referred to.

The operation of the first described embodiment of my invention is as follows: The fan 10 is operated to continuously circulate air from the storage compartment of the refrigerator into and through the inlet flue 8, through the refrigerating compartment in the casing 6 and back into the storage compartment through the outlet flue 9. As described above a cooling agent is intermittently supplied to the coil 11 and when a cycle of operation of the cooling unit is begun the cooling agent is so supplied to cool the coil. When the comparatively warm air enters the refrigerating compartment through the inlet flue 8 some of the moisture contained in the air will be condensed to form frost on the coil 11 and as the air circulates through the refrigerating compartment it will be cooled before it is discharged back into the storage compartment through the outlet flue 9. After the storage compartment has been sufficiently cooled operation of the mechanism supplying the cooling agent to the coil 11 is stopped by any suitable expedient. As the circulation of air continues the comparatively warm air passing through the refrigerating compartment will melt the frost on the coil 11, and when this melting occurs the air will pick up some of the condensed moisture and will be cooled by the melting of the frost as well as by contact with the coils and with the top and bottom walls of the casing 6 which have a conductive connection through the rails 14 with the coils and will therefore be cooled during the period in which a cooling agent is being ac-

tively supplied. As the melting continues any gases or vapors contained in the air circulating through the refrigerating compartment will be condensed and will flow with the water resulting from the melting of the frost through the drain pipe 15. When the cooling effect of the parts of the cooling unit and the melting of the frost is no longer sufficient to maintain the desired low temperature in the refrigerator the supply mechanism will again be operated to supply the cooling agent to the coil 11 and the cycle will be repeated.

If the cooling coil 11 is arranged as shown in the figures with the cooling agent entering it at the inlet end of the refrigerating compartment and flowing through the coil generally towards the outlet end of the compartment, the part of the coil nearest the inlet will be coldest, as described above, and operation of the unit thereby will be enhanced. The warm air will strike the coldest part of the coil first and the condensation of moisture therefore will be centralized to a great extent on the coil nearest the inlet. Then when the coil is not being cooled by an active agent the warm air will be concentrated on the same part of the coil and the frost will be melted most effectively.

A proper speed of the air through the refrigerating compartment must be maintained to get the greatest advantage from the cycle of operation described above and the speed and other conditions of this circulation will be governed by the size, number and arrangement of the fins 13. Likewise, the speed of circulation through the refrigerating compartment directly controls the speed of circulation through the storage compartment and if the air is circulated too rapidly through the latter compartment dehydration of the foodstuffs contained therein may result. Obviously, if the number of fins is increased a greater back pressure in the refrigerating compartment will be created and the speed of circulation therethrough will be diminished. Inversely, if the number of fins is decreased the back pressure will be lessened and the speed will be increased.

Under proper conditions the air in the refrigerator will be kept moist and cold and very little dehydration will occur. Interchange of odors between various foodstuffs will be minimized because as the vapors given off by them are condensed and carried off through the drain pipe 15 the air in the refrigerator will be kept fresh and clean. Furthermore, the "carry over" of the unit will be much longer than the period of active operation because every cooling effect of the unit in addition to cooling by the melting of the frost will be utilized. Particularly during the period when the coil is operating the cooling of the storage compartment will be aided by conduction to the upper wall of the

casing 6, which wall is exposed to the storage compartment and has a conductive connection with the cooling coil through the rails 14.

The cycle of operation of the embodiment shown in Fig. 2 is substantially the same as that above described with the exception that the circulation will be upward through the inlet and downward through the outlet, as shown by the arrows in Fig. 2. In a unit of this latter type flow through the refrigerating compartment and, in turn, through the storage compartment may be more rapid than the flow desirable in the other form of device. Because of its size a rapid flow in a large cooler will not have a dehydration effect as such a flow would have within a smaller area.

While in the drawings attached hereto and in the above description I have disclosed embodiments of my invention in which the unit is placed at the top and bottom of a refrigerator I do not intend to limit myself to any particular position of the unit in a refrigerator. Obviously, under different conditions the unit may be placed in any desired position and the size, shape and arrangement of the various parts may be varied within wide limits without deviating from the spirit of my invention as included in appended claims.

What I claim as new and desire to secure by Letters Patent, is:—

1. A cooling unit for refrigerators comprising a casing forming a refrigerating compartment, a cooling coil included in said compartment, said refrigerating compartment having an inlet from and an outlet to the storage compartment of the refrigerator in which said unit is used, means for circulating air through said inlet into and through said refrigerating compartment and through said outlet back into said storage compartment, and a plurality of fins surrounded by said coil for regulating the circulation of air therethrough.

2. A cooling unit for refrigerators comprising a casing forming a refrigerating compartment, a cooling coil included in said compartment and having its convolutions extending substantially transversely thereof, said refrigerating compartment having an inlet from and an outlet to the storage compartment of the refrigerator in which said unit is used, means for continuously circulating air through said inlet into and through said refrigerating chamber and through said outlet back into said storage compartment, and a plurality of longitudinally extending fins mounted within the convolutions of said coil for regulating said circulation of air.

3. A cooling unit for refrigerators comprising a casing forming a refrigerating compartment, a cooling coil included in said compartment, means for intermittently supplying a cooling agent to said coil, said coil being

arranged whereby said cooling agent flows therethrough from one end of said compartment generally towards the other end thereof, and mechanical means for continuously circulating air from the storage compartment of the refrigerator in which said unit is used through said refrigerating compartment in the direction of said flow.

4. A cooling unit for refrigerators comprising a casing forming a refrigerating compartment, said refrigerating compartment having an inlet from and an outlet to the storage compartment of the refrigerator in which said unit is used, a cooling coil included in said refrigerating compartment and extending between said inlet and said outlet, means for intermittently supplying a cooling agent to said coil and said coil being arranged whereby said cooling agent flows therethrough from the end thereof nearest said inlet generally towards the end thereof nearest said outlet, and mechanical means for continuously circulating air from said storage compartment through said inlet into and through said refrigerating compartment and through said outlet back into said storage compartment.

5. A cooling unit for refrigerators comprising a casing of conductive material forming a refrigerating compartment, a cooling coil included in said compartment, a conductive connection between said coil and a wall of said casing, and mechanical means for circulating through said refrigerating compartment air from the storage compartment of the refrigerator in which said unit is used.

6. A cooling unit for refrigerators comprising a casing forming a refrigerating compartment, said casing having a wall thereof separating said refrigerating compartment from the storage compartment of the refrigerator in which said unit is used and said wall being of conductive material, a cooling coil included in said refrigerating compartment, a conductive connection between said coil and said wall, and mechanical means for continuously circulating through said refrigerating compartment air from said storage compartment.

7. A cooling unit for refrigerators comprising a casing forming a refrigerating compartment, said casing having a wall thereof separating said refrigerating compartment from the storage compartment of the refrigerator in which said unit is used and said wall being of conductive material, a cooling coil included in said refrigerating compartment, a conductive connection between said coil and said wall, means for intermittently supplying a cooling agent to said coil, and mechanical means for continuously circulating through said refrigerating compartment air from said storage compartment.

8. A cooling unit for refrigerators com-

prising a casing of conductive material forming a refrigerating compartment, said casing having a wall thereof separating said refrigerating compartment from the storage compartment of the refrigerator in which said unit is used, a cooling coil included in said refrigerating compartment, a conductive connection between said coil and said wall separating said compartments, means for intermittently supplying a cooling agent to said coil, and mechanical means for continuously circulating through said refrigerating compartment air from said storage compartment.

9. A cooling unit for refrigerators comprising a casing of conductive material forming a refrigerating compartment, said refrigerating compartment having an inlet from and an outlet to the storage compartment of the refrigerator in which said unit is used, said casing having a wall thereof separating said refrigerating compartment from said storage compartment, a cooling coil included in said refrigerating compartment and extending between said inlet and said outlet, a conductive connection between said coil and said wall separating said compartments, means for intermittently supplying a cooling agent to said coil, said coil being arranged whereby said cooling agent flows therethrough from the end thereof nearest said inlet generally towards the end thereof nearest said outlet, mechanical means for continuously circulating air from said storage compartment through said inlet into and through said refrigerating compartment and through said outlet back into said storage compartment, a plurality of longitudinally extending fins mounted in said refrigerating compartment for regulating said circulation of air, and a drain pipe leading from said unit to an outside place of discharge.

10. A refrigerator comprising a food storage compartment and a confined zone separate from the food storage compartment forming a refrigerating compartment, a cooling coil included in said compartment, means for intermittently supplying a cooling agent to said coil, said coil being arranged whereby said cooling agent flows therethrough from one end of said compartment generally towards the other end thereof, and mechanical means for continuously circulating air from the storage compartment of the refrigerator in which said unit is used through said refrigerating compartment in the direction of said flow.

11. A refrigerator comprising a food storage compartment and a confined zone separate from the food storage compartment forming a refrigerating compartment, said refrigerating compartment having an inlet from and an outlet to the storage compartment of the refrigerator in which said unit is used, a cooling coil included in said refrigerating compartment and extending between

5 said inlet and said outlet, means for intermittently supplying a cooling agent to said coil and said coil being arranged whereby said cooling agent flows therethrough from the end thereof nearest said inlet generally towards the end thereof nearest said outlet, and mechanical means for continuously circulating air from said storage compartment through said inlet into and through said refrigerating compartment and through said outlet back into said storage compartment.

10 12. A cooling unit for refrigerators comprising a casing forming a refrigerating compartment, a cooling coil included in said compartment, said refrigerating compartment having an inlet from and an outlet to the storage compartment of the refrigerator in which said unit is used, mechanical means for circulating air through said inlet into and through said refrigerating compartment, said cooling coil having a plurality of convolutions extending transversely of said refrigerating compartment and a plurality of longitudinally extending fins positioned within the convolutions of said coil for regulating the circulation of air therethrough.

15 13. A cooling unit for refrigerators comprising a casing forming a refrigerating compartment, a cooling coil included in said compartment, said refrigerating compartment having an inlet from and an outlet to the storage compartment of the refrigerator in which said unit is used, mechanical means for circulating air through said inlet into and through said refrigerating compartment, and a plurality of fins extending longitudinally of said refrigerating compartment from one end of said coil to the other for regulating the circulation of air therethrough.

20 14. A refrigerator comprising a food storage compartment and a refrigerating compartment extending longitudinally along a horizontal wall of said refrigerator, a cooling coil included in said refrigerating compartment, means for intermittently supplying a cooling agent to said coil, said refrigerating compartment having an inlet from said storage compartment at one end thereof and an outlet to said storage compartment at the other end thereof, mechanical means for continuously circulating air through said inlet into and through said refrigerating compartment and through said outlet into said storage compartment whereby air will be taken from said storage compartment at one end thereof and will be discharged into said storage compartment at the other end thereof after it has been cooled in said refrigerating compartment.

25 15. A refrigerator comprising a food storage compartment and a refrigerating compartment extending longitudinally along a horizontal wall of said refrigerator, a cooling coil included in said refrigerating com-

partment, means for intermittently supplying a cooling agent to said coil, said refrigerating compartment having an inlet from said storage compartment at one end thereof and an outlet to said storage compartment at the other end thereof, mechanical means for continuously circulating air through said inlet into and through said refrigerating compartment and through said outlet into said storage compartment whereby air will be taken from said storage compartment at one end thereof and will be discharged into said storage compartment at the other end thereof after it has been cooled in said refrigerating compartment, and a plurality of longitudinally extending fins arranged in said refrigerating compartment for regulating the circulation of air therethrough.

30 16. A refrigerator comprising a food storage compartment and a refrigerating compartment extending longitudinally along a horizontal wall of said refrigerator, a cooling coil included in said refrigerating compartment, means for intermittently supplying a cooling agent to said coil, said refrigerating compartment having an inlet from said storage compartment at one end thereof and an outlet to said storage compartment at the other end thereof, mechanical means for continuously circulating air through said inlet into and through said refrigerating compartment and through said outlet into said storage compartment whereby air will be taken from said storage compartment at one end thereof and will be discharged into said storage compartment at the other end thereof after it has been cooled in said refrigerating compartment, a plurality of longitudinally extending fins arranged in said refrigerator compartment for regulating the circulation of air therethrough, and said coil being arranged whereby said cooling agent flows therethrough generally in the direction of the circulation of air through said refrigerating compartment.

35 17. A cooling unit for refrigerators comprising a casing consisting of a plurality of separable hood portions of conductive material adapted and arranged to form a refrigerating compartment, a cooling coil included in said compartment, said compartment having an inlet from and an outlet to the storage compartment of said refrigerator in which said unit is used, and mechanical means for circulating air through said inlet into and through said refrigerating compartment and through said outlet back into said storage compartment.

40 18. A cooling unit for refrigerators comprising a casing consisting of a plurality of separable hood portions adapted and arranged to form a refrigerating compartment, a cooling coil included in said compartment and substantially co-extensive therewith,

said coil consisting of a plurality of independently removable sections each of which coincides in size and shape with one of said separable hood portions, said refrigerating compartment having an inlet from and an outlet to the storage compartment of the refrigerator in which said unit is used, and mechanical means for circulating air through said inlet into and through said refrigerating compartment and through said outlet back into said storage compartment.

19. A cooling unit for refrigerators comprising a casing forming a refrigerating compartment, a cooling coil included in said compartment, said refrigerating compartment having an inlet from and an outlet to the storage compartment of the refrigerator in which said unit is used, mechanical means for circulating air through said inlet into and through said refrigerating compartment and through said outlet back into said storage compartment, and a plurality of fins arranged in said refrigerating compartment and positioned to divide said compartment into a plurality of longitudinally extending air channels whereby the circulation of air through said refrigerating compartment will be regulated.

20. A refrigerator comprising a food storage compartment and a refrigerating compartment, a cooling coil included in said refrigerating compartment, means for intermittently supplying a cooling agent to said coil, said refrigerating compartment having an inlet from and an outlet to said storage compartment, mechanical means for circulating air through said inlet into and through said refrigerating compartment and through said outlet back into said storage compartment, and a plurality of fins arranged in said refrigerating compartment and positioned to divide said compartment into a plurality of longitudinally extending air channels whereby the circulation of air through said refrigerating compartment will be regulated.

In witness whereof I have signed my name to the foregoing specification.

JOHN S. BOOTH.
